UNITED STATES PATENT OFFICE

JOSEPH N. BORROUGHS, OF PIEDMONT, AND CHARLES A. OLD, OF OAKLAND, CALIFORNIA, ASSIGNORS TO OAKLAND-CALIFORNIA TOWEL COMPANY, OF OAKLAND, CALIFORNIA, A CORPORATION OF CALIFORNIA

AUTOMATIC TOWEL CABINET

Application filed August 30, 1932. Serial No. 630,992.

This invention is an automatic towel cabinet, which is especially adapted for use in public wash rooms as directed to hotels, theatres, railway stations and other public places, and is intended to provide a completely sanitary towel service.

The main object of the invention is to provide a towel cabinet in which the towel is normally completely enclosed, and in which a clean portion of towel is presented for use without the necessity of contacting the hands with any portion of the equipment or with the towel.

Another object of the invention is to provide a towel cabinet as outlined, which is operated by a foot treadle, which automatically opens a slide door providing access to the towel and feeds a predetermined portion of clean towel from a roll of toweling in position for use each time the treadle is depressed, the door automatically closing when the treadle is released.

Another object of the invention is to provide a device as outlined in which complete closing of the door is required before an additional clean towel can be fed for use, obviating waste of clean toweling which might occur if all movements of the treadle were to feed the toweling.

Other objects and advantages of the invention will become apparent as the following description is read on the drawings forming a part of this specification and in which similar reference characters are used to indicate similar parts throughout the several views and in which:

Fig. 1 is a front view of the invention showing the treadle depressed, the slide door open and the towel presented for use.

Fig. 2 is a transverse sectional elevation of the invention with the front door and slide door both open.

Fig. 3 is a view similar to Fig. 2 except with the slide door closed and including the web path and roll of toweling.

Fig. 4 is a front elevation of the invention with the front door open and slide door closed.

Fig. 5 is a fragmentary side view of the towel feeding mechanism with rolls removed.

Fig. 6 is a front view of Fig. 5 and including the ends of the rolls.

Fig. 7 is a detail view of the stop mechanism.

Fig. 8 is a detail view of the slide door lift rod connection.

Fig. 9 indicates the urging means for the idle rollers.

Fig. 10 is a detail view of the treadle connection for operating the slide door.

Fig. 11 is a fragmentary front elevation of the feed mechanism housing showing the lower feed roll and guard.

Fig. 12 is a sectional view showing the rear support for the feed mechanism housing.

Fig. 13 is a section taken on line 13—13 of Fig. 11.

Fig. 14 is a section taken on line 14—14 of Fig. 11.

The invention consists of a cabinet which is normally entirely closed, and which is provided with a front door for gaining access to the interior of the cabinet, the front door being provided with a slide door for gaining access to the towel loop: A rack for supporting a roll of toweling, feeding mechanism for the toweling, driving mechanism for the feeding mechanism, actuating mechanism for the driving mechanism, lifting mechanism for the slide door, retarding mechanism for the closing of the slide door and governing means for the feeding mechanism, the entire unit being operated by a single depression of the foot treadle, the governing mechanism preventing partial feeding of the towel or the feeding of a second portion of towel until a full cycle is completed and the slide door is fully closed.

The cabinet consists of sides 15 and 16, back 17, top 18, bottom 19 and a front foot panel 20 forming a pocket for the reception of soiled toweling.

The front door 21 is hinged as indicated at 22 and has an opening 23 at a suitable height for convenient use of the towel. This opening is normally closed by a slide door 24 which is provided with tongues 25 slidable in grooves 26 and provided with a hinged pivot member 27. A slot 28 is provided in the front foot panel 20 for the treadle.

The towel roll supporting rack consists of a bottom 29, a diagonal front panel 30, the upper edge of which is provided with a cylindrical metal guard 31, and sides 32 for positioning the roll of toweling 33.

The feeding mechanism consists of two driven rollers 34 and 35 and cooperating resiliently urged idle rollers 36 and 37. The driven rollers are preferably covered with rubber so as to provide the necessary friction for feeding the toweling. A guard 38 is pivotally suspended beneath the idle roller 36 to prevent creeping of the toweling about the roller.

15 A guard is pivotally suspended from the driven roller 35 and consists of a plurality of spaced hangers 39 which are rotatable in grooves formed in the roller 35 and are secured at their lower ends by a bar 40, and is adapted to prevent creeping of the toweling about the roller.

20 A guard 41 is pivotally suspended and normally supported by the toweling on roller 35 and is adapted to prevent the toweling from above engaging the lower rolls, and may be raised to permit threading of the web.

25 The idle rollers are rotatably mounted in bearing blocks 42 which have flattened sides and are slidable but non-rotatable in slots 43 formed in the side members 44 and 45 of the feed mechanism housing. Springs 46 have their opposite ends respectively secured in the bearing blocks and to the roll housing, and urge the idle rollers into contact with the driven or feed rollers.

30 The driving mechanism consists of sprockets 47 and 48 secured on the journals 49 and 50 of feed rolls 35 and 34. A sprocket 51 rotatably mounted on a pivot 52, and a circumambient sprocket chain 53 cooperating with the three sprockets, the ends of journals 49 and 50 being rotatably mounted in bearings secured in the end plate 54.

35 Rotatably mounted on pivot 52 is a ratchet 55, which cooperates with a pawl 56 which is pivotally secured at 57 to the sprocket 51, a spring 58 urging the pawl to cooperate with the sprocket.

40 Fixedly secured to or integral with the ratchet 55 is a sprocket 59 which cooperates with a chain 60, the pivot 52 being secured in the housing plates 44 and 54.

45 The journals at the other end of rollers 34 and 35 are rotatably mounted in bearings secured in the plate 45 as shown at 61 and 62.

50 A back plate 63 together with end plates 45 and 54 and intermediate plate 44 completes the housing for the feed mechanism and is removably mounted in the cabinet by means of a rear angle support 64 the horizontal leg of which is bent at right angles forming brackets 65 which are secured to the sides of the cabinet. The vertical leg is provided with slots 66 which are adapted to receive the

side and intermediate walls 45, 54 and 44, thus positioning the housing in the cabinet. Screws 67 may be provided for fixidly securing the housing in position, if desired. The forward end of the housing is supported by 70 brackets 68 and 69 which are mounted on the cabinet sides.

The actuating mechanism for the driving mechanism consists of a treadle 70 which is pivoted at 71 and operates through a slot 75 28 in the front foot-panel. A connecting rod 72 is secured at one end to the chain 60 which cooperates with the sprocket 59 and has the other end attached to the treadle through an interposed tension spring 73, the other end of chain 60 being connected to a lever 74 which is pivoted at 75 and which is resiliently retracted by a spring 76, which is anchored to the side of the cabinet.

The lifting mechanism for the slide door 85 consists of a connecting rod 77 connected at one end to the treadle 70 and at the other end to a chain 78 which cooperates with a sprocket or hub 79 which is integral with a lever 80, the sprocket being rotatably mounted in a housing 81 which is secured to the side of the cabinet.

The hinged pivot member 27 is secured adjacent the lower edge of the slide door and consists of a strap member 27 to which is hinged an ear 82 into which is pivoted a connecting rod 83, the other end of this connecting rod being pivotally connected at 84 to lever 80.

The retarding mechanism for the closing 100 of the slide door consists of a connecting rod 85 which has one end connected to the treadle 70 and the other end connected to a lever 86 which has one end pivotally secured as at 87 to the side of the cabinet, the other end cooperating with the connecting rod 88 of an air cylinder 89, this air cylinder being of the usual construction having a regulating valve 90 for governing the retarding action of the piston, this cylinder being pivotally mounted as indicated at 91.

The governing means for the feeding mechanism consists of a pawl 92 which is pivotally mounted on plate 54 as indicated at 93 and is adapted to lock the chain 53 against movement by cooperation of the tongue 94 with the chain rollers, an extension 95 having pivotally connected thereto a connecting rod 96 which is slidable in the guide 97 and has a recess formed inside which is adapted to cooperate with a leaf spring 98 to resiliently lock the pawl 92 in engagement with the chain 53. Secured to the lower end of rod 96 is a yoke 99 which straddles connecting rod 72 which is freely slidable in the yoke. 120 Adjustably secured on connecting rod 72 are two collars 100 and 101 which are adapted to cooperate with the yoke 99.

125 The web path follows from the roll of toweling 33 up the inclined front as indi- 130

cated at 102 thence over the cylindrical member 31, thence downwardly and back of rollers 34 as indicated at 103 thence under and between rollers 34 and 36, a loop being formed at 104 extending to the bottom of door opening 23 upwardly over roller 35 thence between rollers 35 and 37, thence being free to deposit in the receptacle formed at the bottom of the cabinet as indicated at 105 and 106.

The loading of the device is as follows: The front door is opened, a roll of toweling is placed in the rack 29, threaded over the front cylindrical element, passed about roller 34, deflector 41 preventing rollers 35 and 37 cooperating with any portion of the toweling, the end of the toweling is then passed upwardly between rollers 34 and 36 and sufficient toweling drawn through to form the loop 104 the end 20 of the toweling being then passed under deflector 41 and downwardly between rollers 35 and 37. The device is then ready for use.

The operation of the towel cabinet is as follows:

With the front door closed the treadle 70 is depressed which through connecting rod 77, chain 78, sprocket 79, swings lever 80 from the position shown in Fig. 3 to that shown in Fig. 2 which through connecting rod 83 raises slide door 24 from the position shown in Fig. 3 to that shown in Fig. 2. Coincidently the piston in cylinder 89 is retracted through connecting rod 85 and lever 86 setting the retarding mechanism. Coincidently through spring 73, connecting rod 72, chain 60, ratchet 55 is rotated coincidently with pawl 56 and driving thereby sprockets 48 and 47 through chain 53, thereby feeding a length of toweling depending on the spacing of the collars 100 and 101.

As the treadle reaches the bottom of its stroke collar 101 engages yoke 99, pulling down connecting rod 96 and causing tongue 94 on pawl 92 to engage chain 53 preventing further movement of the toweling, the spring 98 engaging recess 107 and retaining the pawl in locked position. As the treadle is released the weight of the slide door and various springs react against the piston in cylinder 89 which retards the movement of the slide door 24, spring 76 retracting chain 60 and coincidently ratchet 55 preparatory for the next operation. The final return movement of treadle 70 which coincides with the final closing movement of slide door 24 permits collar 100 to cooperate with yoke 99, raising connecting rod 96 and releasing tongue 94 from chain 53.

From the foregoing it will be noted that there can be no feeding movement of the toweling until the full cycle is completed after depression of the treadle. The feeding mechanism is positively locked by the pawl 92 during the entire return movement of the

treadle, which is obviously coincident with the closing of the slide door.

The device is sanitary, does not require contact of the hands with any portion of soiled toweling, the toweling is always enclosed except during the time of use and there is no possibility of soiled toweling being presented for use.

Having described an operative device, it will be understood that variations in construction and arrangement of parts which are consistent with the appended claims may be resorted to without detracting from the spirit or scope of the invention or sacrificing any of its advantages.

We claim:

1. A towel cabinet in combination, adjustable feeding means for feeding toweling in predetermined lengths, a treadle, actuating means operable by depression of said treadle for actuating said feeding means, and locking means for said feeding means connected to portions of the actuating means and actuated by the final downward movement of said treadle and released by the final upward movement of said treadle.

2. A towel cabinet, in combination, a closure for said cabinet normally retained in closed position, adjustable feeding means for feeding toweling in predetermined lengths, a treadle, means operable by depression of said treadle for coincidently actuating said feeding means and opening said closure and locking means for said feeding means connected to portions of said actuating means and actuated by the final downward movement of said treadle and released by the final upward movement of said treadle.

3. In a towel cabinet, a normally closed door means for feeding toweling in predetermined portions in registry with said door, a treadle, means actuated by depression of said treadle for operating said feeding means and coincidently opening said door and means cooperating with said treadle actuated means for locking said feeding means coincidently with the final downward movement of said treadle and for releasing said locking means coincidently with the final upward movement of said treadle.

4. A towel cabinet, in combination, a closure for said cabinet normally retained in closed position, adjustable feeding means for feeding toweling in predetermined lengths, a treadle, means operable by depression of said treadle for coincidently actuating said feeding means and opening said closure, and locking means for said feeding means connected to portions of said actuating means and actuated by the final downward movement of said treadle and released by the final upward movement of said treadle, said closure consisting of a door vertically slidable to open position, and retarding means for retarding the closing movement of said door, to prevent

injury to the user or operator, said retarding means comprising an air cylinder operatively connected to said treadle to retard the return movement thereof.

- 335 5. A towel cabinet, in combination, a closure for said cabinet normally retained in closed position, adjustable feeding means for feeding toweling in predetermined lengths, a treadle, means operable by depression of said treadle for coincidentally actuating said feeding means and opening said closure, and locking means for said feeding means connected to portions of said actuating means and actuated by the final downward movement of said treadle and released by the final upward movement of said treadle, said feeding means consisting of two pairs of rolls spaced apart, each pair consisting of a master roll and a peripherally cooperating idler roll, a driven sprocket fixed to one end of each master roll, a drive sprocket freely rotatable and cooperating with said driven sprockets through a circumambient chain, said actuating means comprising a pawl on said drive sprocket, a ratchet coaxial with said drive sprocket, an actuating sprocket integral with or secured to said ratchet and coaxial therewith and a chain cooperating with said actuating sprocket and with said treadle.
- 30 6. A towel cabinet, in combination, a closure for said cabinet normally retained in closed position, adjustable feeding means for feeding toweling in predetermined lengths, a treadle, means operable by depression of said treadle for coincidentally actuating said feeding means and opening said closure, and locking means for said feeding means connected to portions of said actuating means and actuated by the final downward movement of said treadle and released by the final upward movement of said treadle, said closure consisting of a door vertically slidable to open position, and retarding means for retarding the closing movement of said door, to prevent injury to the user or operator, said retarding means comprising an air cylinder operatively connected to said treadle to retard the return movement thereof, said feeding means consisting of two pairs of rolls spaced apart, each pair consisting of a master roll and a peripherally cooperating idler roll, a driven sprocket fixed to one end of each master roll, a drive sprocket freely rotatable and cooperating with said driven sprockets through a circumambient chain, said actuating means comprising a pawl on said drive sprocket, a ratchet coaxial with said drive sprocket, an actuating sprocket integral with or secured to said ratchet and coaxial therewith, and a chain cooperating with said actuating sprocket and with said treadle.

- 60 7. In a towel cabinet, a normally closed door vertically slidable to open position, a treadle, feeding means for feeding a web of toweling in predetermined lengths, actuating

means operably connected to the treadle for actuating said feeding means, locking means for said feeding means cooperating with said actuating means to lock the feeding means with the final downward movement of the treadle and to release the feeding means with the final upward movement of the treadle, door raising means actuated by depression of said treadle and retarding means for retarding the closing movement of said door, whereby injury to the user is prevented when the treadle is released.

70 8. In a towel cabinet, a normally closed door vertically slidable to open position, a treadle, feeding means for feeding a web of toweling in predetermined lengths, actuating means for said feeding means, locking means for said feeding means cooperating with said actuating means to lock the feeding means with the final downward movement of the treadle and release the feeding means with the final upward movement of the treadle, door raising means actuated by depression of said treadle and retarding means for retarding the closing movement of said door, whereby injury to the user is prevented when the treadle is released, said feeding means consisting of a plurality of pairs of rolls, each pair consisting of a master roll and a peripherally cooperating idler roll, a chain drive for driving said master rolls in unison, said actuating means consisting of a ratchet and pawl for driving said driving means, a sprocket fixed to said pawl and a chain cooperating intermediate its length with the sprocket and having one end connected to the treadle through an interposed connecting rod and a tension spring, and a spring cooperating between the other end and the cabinet for retracting the chain and raising the treadle.

80 9. In a towel cabinet, a normally closed door vertically slidable to open position, a treadle, feeding means for feeding a web of toweling in predetermined lengths, actuating means for said feeding means, locking means for said feeding means cooperating with said actuating means to lock the feeding means with the final downward movement of the treadle and release the feeding means with the final upward movement of the treadle, door raising means actuated by depression of said treadle and retarding means for retarding the closing movement of said door, whereby injury to the user is prevented when the treadle is released, said feeding means consisting of a plurality of pairs of rolls, each pair consisting of a master roll and a peripherally cooperating idler roll, a chain drive for driving said master rolls in unison, said actuating means consisting of a ratchet and pawl for driving said driving means, a sprocket fixed to said pawl and a chain cooperating intermediate its length with the sprocket and having one end connected to the treadle through an interposed connecting rod

and a tension spring, and a spring cooperating between the other end and the cabinet for retracting the chain and raising the treadle, said locking means comprising an intermediately pivoted pawl mounted for cooperation with said chain drive, an actuating rod and a guide therefor, a recess formed in the side of the actuating rod, a leaf spring mounted to cooperate with said recess to retain the pawl in engagement with the chain drive, two spaced apart collars on said interposed connecting rod and adjustably secured thereon, and a yoke on said actuating rod for cooperation with said collars, whereby when the actuating rod is moved by the connecting rod to one position, the pawl engages the chain drive and the leaf spring resiliently secure the actuating rod, movement of the actuating rod to its other position releasing the pawl from the chain drive.

10. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means with the final downward movement of the treadle and to release the feeding means with the final upward movement of the treadle, door raising means actuated by depression of said treadle and retarding means for retarding the closing movement of said door, whereby injury to the user is prevented when the treadle is released, said door raising means comprising a lever pivotally mounted, a connecting rod cooperating between the door and the lever to raise the door, a hub on the lever, and a chain cooperating between the periphery of the hub and the treadle, whereby depression of the treadle will raise the door.

11. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means with the final downward movement of the treadle and to release the feeding means with the final upward movement of the treadle, door raising means actuated by depression of said treadle and retarding means for retarding the closing movement of said door, whereby injury to the user is prevented when the treadle is released, said feeding means consisting of a plurality of pairs of rolls, each pair consisting of a master roll and a peripherally cooperating idler roll, a chain drive for driving said master rolls in unison, said actuating means consisting of a ratchet and pawl for driving said driving means, a sprocket fixed to said pawl and a chain cooperating intermediate its length with the sprocket and having one end connected to the treadle through an interposed connecting rod and a tension spring, and a spring cooperating between the other end and the cabinet for retracting the chain and raising the treadle, said locking means comprising an intermediately pivoted pawl mounted for cooperation with said chain drive, an actuating rod and a guide therefor, a recess formed in the side of the actuating rod, a leaf spring mounted to cooperate with said recess to retain the pawl in engagement with the chain drive, two spaced apart collars on said interposed connecting rod and adjustably secured thereon, and a yoke on said actuating rod for cooperation with said collars, whereby when the actuating rod is moved by the connecting rod to one position, the pawl engages the chain drive and the leaf spring resiliently secure the actuating rod, movement of the actuating rod to its other position releasing the pawl from the chain drive, said door raising means comprising a lever pivotally mounted, a connecting rod cooperating between the door and the lever to raise the door, a hub on the lever, and a chain cooperating between the periphery of the hub and the treadle, whereby depression of the treadle will raise the door.

driving means, a sprocket fixed to said pawl and a chain cooperating intermediate its length with the sprocket and having one end connected to the treadle through an interposed connecting rod and a tension spring, and a spring cooperating between the other end and the cabinet for retracting the chain and raising the treadle, said door raising means comprising a lever pivotally mounted, a connecting rod cooperating between the door and the lever to raise the door, a hub on the lever, and a chain cooperating between the periphery of the hub and the treadle, whereby depression of the treadle will raise the door.

12. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means with the final downward movement of the treadle and to release the feeding means with the final upward movement of the treadle, door raising means actuated by depression of said treadle and retarding means for retarding the closing movement of said door, whereby injury to the user is prevented when the treadle is released, said feeding means consisting of a plurality of pairs of rolls, each pair consisting of a master roll and a peripherally cooperating idler roll, a chain drive for driving said master rolls in unison, said actuating means consisting of a ratchet and pawl for driving said driving means, a sprocket fixed to said pawl and a chain cooperating intermediate its length with the sprocket and having one end connected to the treadle through an interposed connecting rod and a tension spring, and a spring cooperating between the other end and the cabinet for retracting the chain and raising the treadle, said locking means comprising an intermediately pivoted pawl mounted for cooperation with said chain drive, an actuating rod and a guide therefor, a recess formed in the side of the actuating rod, a leaf spring mounted to cooperate with said recess to retain the pawl in engagement with the chain drive, two spaced apart collars on said interposed connecting rod and adjustably secured thereon, and a yoke on said actuating rod for cooperation with said collars, whereby when the actuating rod is moved by the connecting rod to one position, the pawl engages the chain drive and the leaf spring resiliently secure the actuating rod, movement of the actuating rod to its other position releasing the pawl from the chain drive, said door raising means comprising a lever pivotally mounted, a connecting rod cooperating between the door and the lever to raise the door, a hub on the lever, and a chain cooperating between the periphery of the hub and the treadle, whereby depression of the treadle will raise the door.

13. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means with the final downward movement of the treadle and to release the feeding means with the final upward movement of the treadle, door raising means actuated by depression of said treadle and retarding means for retarding the closing movement of said door, whereby injury to the user is prevented when the treadle is released, said feeding means consisting of a plurality of pairs of rolls, each pair consisting of a master roll and a peripherally cooperating idler roll, a chain drive for driving said master rolls in unison, said actuating means consisting of a ratchet and pawl for driving said driving means, a sprocket fixed to said pawl and a chain cooperating intermediate its length with the sprocket and having one end connected to the treadle through an interposed connecting rod and a tension spring, and a spring cooperating between the other end and the cabinet for retracting the chain and raising the treadle, said locking means comprising an intermediately pivoted pawl mounted for cooperation with said chain drive, an actuating rod and a guide therefor, a recess formed in the side of the actuating rod, a leaf spring mounted to cooperate with said recess to retain the pawl in engagement with the chain drive, two spaced apart collars on said interposed connecting rod and adjustably secured thereon, and a yoke on said actuating rod for cooperation with said collars, whereby when the actuating rod is moved by the connecting rod to one position, the pawl engages the chain drive and the leaf spring resiliently secure the actuating rod, movement of the actuating rod to its other position releasing the pawl from the chain drive, said door raising means comprising a lever pivotally mounted, a connecting rod cooperating between the door and the lever to raise the door, a hub on the lever, and a chain cooperating between the periphery of the hub and the treadle, whereby depression of the treadle will raise the door.

a chain cooperating between the periphery of the hub and the treadle, whereby depression of the treadle will raise the door.

13. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means with the final downward movement of the treadle and to release the feeding means with the final upward movement of the treadle, door raising means actuated by depression of said treadle and retarding means for retarding the closing movement of said door, whereby injury to the user is prevented when the treadle is released, said retarding means comprising an air cylinder operatively connected to said treadle to retard the return movement thereof.

14. A towel cabinet in combination, adjustable feeding means for feeding toweling in predetermined lengths, a treadle, actuating means operable by depression of said treadle for actuating said feeding means, and locking means connected to portions of the actuating means and actuated by the final downward movement of said treadle and released by the final upward movement of said treadle, said locking means consisting of a pawl mounted for cooperative engagement with the feeding means and movable into and out of engagement by the actuating means at the terminals of movement thereof, and means for retaining the pawl in engagement during movement of the actuating means in one direction of movement, whereby the feeding means is locked against movement until movement of the actuating means in said one direction is completed.

15. A towel cabinet, in combination, a closure for said cabinet normally retained in closed position, adjustable feeding means for feeding toweling in predetermined lengths, a treadle, means operable by depression of said treadle for coincidentally actuating said feeding means and opening said closure, and locking means for said feeding means connected to portions of said actuating means and actuated by the final downward movement of said treadle and released by the final upward movement of said treadle, said locking means consisting of a pawl mounted for cooperative engagement with the feeding means and movable into and out of engagement by the actuating means at the terminals of movement thereof, and means for retaining the pawl in engagement during movement of the actuating means in one direction of movement, whereby the feeding means is locked against movement until movement of the actuating means in said one direction is completed.

16. A towel cabinet, in combination, a closure for said cabinet normally retained in closed position, adjustable feeding means for feeding toweling in predetermined lengths, a treadle, means operable by depression of said treadle for coincidentally actuating said feeding means and opening said closure, and locking means for said feeding means connected to portions of said actuating means and actuated by the final downward movement of said treadle and released by the final upward movement of said treadle, said feeding means consisting of two pairs of rolls spaced apart, each pair consisting of a master roll and a peripherally cooperating idler roll, a driven sprocket fixed to one end of each master roll, a drive sprocket freely rotatable and cooperating with said driven sprockets through a circumambient chain, said actuating means comprising a pawl on said drive sprocket, a ratchet coaxial with said drive sprocket, an actuating sprocket integral with or secured to said ratchet and coaxial therewith and a chain cooperating with said actuating sprocket and with said treadle, said locking means consisting of a pawl mounted for cooperative engagement with the feeding means and movable into and out of engagement by the actuating means at the terminals of movement thereof, and means for retaining the pawl in engagement during movement of the actuating means in one direction of movement, whereby the feeding means is locked against movement until movement of the actuating means in said one direction is completed.

17. A towel cabinet, in combination, a closure for said cabinet normally retained in closed position, adjustable feeding means for feeding toweling in predetermined lengths, a treadle, means operable by depression of said treadle for coincidentally actuating said feeding means and opening said closure, and locking means for said feeding means connected to portions of said actuating means and actuated by the final downward movement of said treadle and released by the final upward movement of said treadle, said closure consisting of a door vertically slidable to open position, and retarding means for retarding the closing movement of said door, to prevent injury to the user or operator, said retarding means comprising an air cylinder operatively connected to said treadle to retard the return movement thereof, said feeding means consisting of two pairs of rolls spaced apart, each pair consisting of a master roll and a peripherally cooperating idler roll, a driven sprocket fixed to one end of each master roll, a drive sprocket freely rotatable and cooperating with said driven sprockets through a circumambient chain, said actuating means comprising a pawl on said drive sprocket, a ratchet coaxial with said drive sprocket, an actuating sprocket integral with or secured to said ratchet and coaxial therewith and a chain cooperating with said actuating sprocket and with said treadle, said locking means consisting of a pawl mounted for cooperative engagement with the feeding means and movable into and out of engagement by the actuating means at the terminals of movement thereof, and means for retaining the pawl in engagement during movement of the actuating means in one direction of movement, whereby the feeding means is locked against movement until movement of the actuating means in said one direction is completed.

- integral with or secured to said ratchet and coaxial therewith, and a chain cooperating with said actuating sprocket and with said treadle, said locking means consisting of a 5 pawl mounted for cooperative engagement with the feeding means and movable into and out of engagement by the actuating means at the terminals of movement thereof, and means for retaining the pawl in engagement 10 during movement of the actuating means in one direction of movement, whereby the feeding means is locked against movement until movement of the actuating means in said one direction is completed. 15 18. In a towel cabinet, a normally closed door vertically slidable to open position, a treadle, feeding means for feeding a web of toweling in predetermined lengths, actuating means operably connected to the treadle 20 for actuating said feeding means, locking means for said feeding means cooperating with said actuating means to lock the feeding means with the final downward movement of the treadle and to release the feeding 25 means with the final upward movement of the treadle, door raising means actuated by depression of said treadle and retarding means for retarding the closing movement of said door, whereby injury to the user is prevented 30 when the treadle is released, said locking means consisting of a pawl mounted for cooperative engagement with the feeding means and movable into and out of engagement by the actuating means at the terminals of 35 movement thereof, and means for retaining the pawl in engagement during movement of the actuating means in one direction of movement, whereby the feeding means is locked against movement until movement of the actuating means in said one direction is completed. 40 19. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means 45 with the final downward movement of the treadle and to release the feeding means with the final upward movement of the treadle, door raising means actuated by depression of said treadle and retarding means for retarding 50 the closing movement of said door, whereby injury to the user is prevented when the treadle is released, said feeding means comprising a plurality of pairs of rolls, each pair consisting of a master roll and a peripherally cooperating idler roll, a chain drive for driving said master rolls in unison, said actuating means comprising a ratchet and pawl for driving said chain drive, a sprocket fixed to said pawl and a chain cooperating in 55 intermediate its length with the sprocket and having one end connected to the treadle through an interposed connecting rod and a tension spring, and a spring cooperating between the other end and the cabinet for retracting the chain and raising the treadle, 60 said locking means consisting of a pawl mounted for cooperative engagement with the feeding means and movable into and out of engagement by the actuating means at the terminals of movement thereof, and means for retaining the pawl in engagement during movement of the actuating means in one direction of movement, whereby the feeding means is locked against movement until movement of the actuating means in said one 65 direction is completed. 70 20. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means with the final downward movement of the 75 treadle and to release the feeding means with the final upward movement of the treadle, door raising means actuated by depression of said treadle and retarding means for retarding the closing movement of said door, whereby injury to the user is prevented when the treadle is released, said door raising means comprising a lever pivotally mounted, a connecting rod cooperating between the door and the lever to raise the door, a hub on 80 the lever, and a chain cooperating between the periphery of the hub and the treadle, whereby depression of the treadle will raise the door, said locking means consisting of a pawl mounted for cooperative engagement 85 with the feeding means and movable into and out of engagement by the actuating means at the terminals of movement thereof, and means for retaining the pawl in engagement during movement of the actuating means in one direction of movement, whereby the feeding means is locked against movement until movement of the actuating means in said one direction is completed. 90 95 100 21. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means with the final downward movement of the treadle and to release the feeding means with the final upward movement of the treadle, door raising means actuated by depression of said treadle and retarding means for retarding the closing movement of said door, whereby injury to the user is prevented when the treadle is released, 105 110 115 120 125 130

leased, said feeding means comprising a plurality of pairs of rolls, each pair consisting of a master roll and a peripherally cooperating idler roll, a chain drive for driving said master rolls in unison, said actuating means comprising a ratchet and pawl for driving said chain drive, a sprocket fixed to said pawl and a chain cooperating intermediate its length with the sprocket and having one end connected to the treadle through an interposed connecting rod and a tension spring, and a spring cooperating between the other end and the cabinet for retracting the chain and raising the treadle, said door raising means comprising a lever pivotally mounted, a connecting rod cooperating between the door and the lever to raise the door, a hub on the lever, and a chain cooperating between the periphery of the hub and the treadle, whereby depression of the treadle will raise the door, said locking means consisting of a pawl mounted for cooperative engagement with the feeding means and movable into and out of engagement by the actuating means at the terminals of movement thereof, and means for retaining the pawl in engagement during movement of the actuating means in one direction of movement, whereby the feeding means is locked against movement until movement of the actuating means in said one direction is completed.

22. In a towel cabinet, a normally closed door vertically slidable to open position, a treadle, feeding means for feeding a web of toweling in predetermined lengths, actuating means operably connected to the treadle for actuating said feeding means, locking means for said feeding means cooperating with said actuating means to lock the feeding means with the final downward movement of the treadle and to release the feeding means with the final upward movement of the treadle, door raising means actuated by depression of said treadle and retarding means for retarding the closing movement of said door, whereby injury to the user is prevented when the treadle is released, said retarding means comprising an air cylinder operatively connected to said treadle to retard the return movement thereof, said locking means consisting of a pawl mounted for cooperative engagement with the feeding means and movable into and out of engagement by the actuating means at the terminals of movement thereof, and means for retaining the pawl in engagement during movement of the actuating means in one direction of movement, whereby the feeding means is locked against movement until movement of the actuating means in said one direction is completed.

23. In a towel cabinet having a chain drive, and actuating means having a connecting rod, locking means comprising an

intermediately pivoted pawl mounted for cooperation with said chain drive, an actuating rod and a guide therefor, a recess formed in the side of the actuating rod, a leaf spring mounted to cooperate with said recess to retain the pawl in engagement with the chain drive, two spaced apart collars on said interposed connecting rod and adjustably secured thereon, and a yoke on said actuating rod for cooperation with said collars, whereby, when the actuating rod is moved by the connecting rod to one position, the pawl engages the chain drive and the leaf spring resiliently secures the actuating rod, movement of the actuating rod to its other position releasing the pawl from the chain drive.

24. In a towel cabinet having feeding means and actuating means therefor having members movable in two directions, locking means consisting of a pawl mounted for cooperative engagement with the feeding means and movable into and out of engagement by the actuating means at the terminals of movement of the members, and means for retaining the pawl in engagement during movement of the members in one direction of movement, whereby the feeding means is locked against movement until movement of the members in said one direction is completed.

In testimony whereof we affix our signature.

JOSEPH N. BORROUGHS.
